CIRCUIT INTERRUPTER

Winthrop M. Leeds, Wilkinsburg, and Benjamin P. Baker, Turtle Creek, Pa., assignors to Westinghouse Electric Corporation, East Pittsburgh, Pa., a corporation of Pennsylvania

Application December 24, 1943, Serial No. 515,536

15 Claims. (Cl. 200—150)

1

This invention relates to circuit interrupters, and, more particularly, to circuit interrupters of the type having arc extinguishing structures in which fluid is forced into the arc stream to effect rapid extinction of the arc.

It was found in testing a circuit interrupter of the type having a nozzle-shaped stationary contact, from which a movable contact was withdrawn and having a plurality of laterally disposed inlet passages spaced along the path of movement of the movable contact, somewhat similar to that shown in U. S. Patent 2,304,529 issued December 8, 1942, to Benjamin P. Baker, and assigned to the same assignee of this invention, that the greater proportion of the oil would flow through the inlet passage adjacent the vented nozzle-shaped contact. It was felt that this greater proportion of flow, which took place adjacent the stationary contact, could be attributed to the restriction of the lower inlet passages by the moving contact and the back pressure from gas produced by the arc. The disadvantage which resulted was inadequate scavenging of the whole arc length by oil flow. It is desirable to have the arc extinguishing fluid traverse the entire arc space whatever the position of the moving contact. Furthermore, during a flushing operation taken on no-load operation of the interrupter, it is also desirable to have the flushing oil pass through the entire arcing region.

It is a general object of our invention to provide a solution for this problem.

Another object is to provide an improved circuit interrupter of the type having a plurality of passages disposed along the path of movement of the moving contact, and to provide valve means for controlling the flow of fluid through the plurality of passages. Preferably, it is desirable to provide valve means which are movable in response to motion of the movable contact which successively opens the passages to permit the flow of fluid therethrough.

Another object is to provide an improved circuit interrupter of the type which causes a flow of fluid substantially transversely of the arc at a level with a moving point in the arc. The moving point may move at a speed which is proportional to the speed of movement of the movable contact.

Another object is to provide an improved circuit interrupter of the type having separable contact means to establish an arc. We associate a chamber with the circuit interrupter having a volume which is contractable during the opening movement of the movable contact means, and

2

which is expandable during the closing movement thereof. We associate valve means with the chamber for causing unidirectional circulation of fluid through the chamber during a complete operation of the interrupter.

Further objects will become apparent upon a reading of the following specification taken in conjunction with the drawings, in which:

Fig. 1 is a circuit interrupter embodying our invention and shown in the closed circuit position;

Fig. 2 is an enlarged vertical sectional view through one of the arc extinguishing units of Fig. 1, the contacts being shown in the partly open circuit position;

Fig. 3 is a view in section taken on the line III—III of Fig. 2;

Fig. 4 is a view in section taken on the line IV—IV of Fig. 2;

Fig. 5 is a circuit interrupter embodying a modification of our invention taken on the line V—V of Fig. 6, the contacts being shown in the partly open circuit position;

Fig. 6 is a view in section taken on the line VI—VI of Fig. 5;

Fig. 7 is another modification of our invention taken on the line VII—VII of Fig. 8, the contacts being shown in the partly open circuit position;

Fig. 8 is a view in section taken on the line VIII—VIII of Fig. 7;

Fig. 9 is a view in section taken on the line IX—IX of Fig. 7;

Fig. 10 is still another embodiment of our invention, the contacts again being shown in the partly open circuit position;

Fig. 11 is a view in section taken on the line XI—XI of Fig. 10; and

Fig. 12 is a view in section taken on the line XII—XII of Fig. 10.

Referring to the drawings and, more particularly, to Fig. 1, the reference numeral 1 designates a tank filled to the level 2 with a suitable arc extinguishing fluid, in this instance oil. Depending from the cover 3 of the tank 1 are a pair of terminal bushings 4 which enclose a pair of terminal studs, not shown. Threaded to the lower end of the terminal studs are a pair of apertured contact feet 5 which are clamped to the terminal studs by clamping studs 6. The contact feet 5 support a pair of arc extinguishing units, generally designated by the reference numeral 7, which are bridged in the closed circuit position, as shown in Fig. 1, by a conducting bridging bar 8, which is reciprocally operated in a vertical direction by an insulating operating

rod 9 to effect the opening and closing of the circuit through the interrupter. The full open-circuit position of the interrupter is shown by the dotted lines 10 of Fig. 1. At the opposed outer ends of the bridging bar 8 are the movable contacts 11 of the interrupter. Since the two units 7 are identical, a description of only one will suffice.

Bolts 13, which extend through the contact feet 5, secure a hollow stationary contact support 14 in place (see Fig. 2). Threadedly secured to the contact support 14 is an annular removable arc resisting stationary contact 15 having an aperture 16 therethrough for forming a vent. As shown in Fig. 2, insulating tie rods 17 and nuts 18 secure a grid structure, generally designated by the reference numeral 19, to the stationary contact support 14.

In this instance the grid structure 19 comprises two types of plates. The first type is herein called an insulating orifice plate and is designated by the reference numeral 20 in Fig. 2. The orifice plate 20 has an aperture 21 centrally formed therein through which moves the movable contact 11. The second type of plate comprises a plurality, in this instance four, segmental insulating plates 23 more clearly shown by the dotted lines in Fig. 4. The segmental insulating plates 23 are rigidly secured in place by the tie rods 17 and they form a plurality of inlet passages 24 between each pair of orifice plates 20.

The movable contact 11 separates from the stationary contact 15 to establish an arc 25 as more clearly shown in Fig. 2. We provide movable valve means comprising a cylindrical slide valve or apertured member 26, the upper end of which is guided by a portion 27 integrally formed with the contact support 14. The lower end of the cylindrical slide valve 26 is threadedly secured at 28 to an offstanding wall 29 integrally formed with the movable contact 11. It will be observed that the cylindrical slide valve 26 and the wall 29 form a chamber, generally designated by the reference numeral 30 in Fig. 2. The movable contact 11 has a passage 32 formed therein which connects the arcing region, generally designated by the reference numeral 33, with the chamber 30. It will be observed that the arc 25 has a fixed arc terminal at the stationary contact 15 and a movable arc terminal at the tip 31 of the movable contact 11.

The cylindrical slide valve 26 and the offstanding wall 29 together form a piston member, generally designated by the reference numeral 41, which moves in response to motion of the movable contact 11 within a piston chamber, generally designated by the reference numeral 42. The piston chamber 42 comprises an insulating cylinder 43, the upper end of which is threadedly secured at 44 to an offstanding flange 45 integrally formed with the stationary contact support 14. The lower end of the insulating cylinder 43 is threadedly secured to a bottom metallic plate 46 which also serves to guide the motion of the moving contact 11.

In this instance four apertures 47 are provided in the cylindrical slide valve 26 to successively cause the opening of the inlet passages 24. It will be observed that the apertures 47 are positioned adjacent the tip 31 of the movable contact 11. Consequently, as the contact 11 moves downwardly one set of inlet passages 24 is sealed up and the next set of inlet passages 24 are opened up. Thus this arrangement permits a very effective use of the oil flow which must traverse the

entire arc space 33 whatever the position of the moving contact 11. Furthermore, since oil flow is above the contact tip 31, being projected toward the point P, the clearance between the moving contact 11 and the grid plates may be reduced to a minimum. This means more restriction of the arc 25 for a given size contact 15, and, therefore, more effective arc interruption.

The operation of the embodiment of our invention shown in Figs. 1-4 will now be explained. In the closed circuit position of the interrupter as shown in Fig. 1, the electrical circuit therethrough comprises left-hand terminal stud, not shown, left-hand contact foot 5, stationary contact support 14, stationary contact 15, movable contact 11, conducting bridging bar 8 through the right-hand arc extinguishing unit 7 in an identical manner to the right-hand terminal stud not shown.

When it is desired to open the electrical circuit passing through the interrupter, or in response to overload conditions existing in the electrical circuit controlled by the interrupter, suitable operating mechanism, not shown, is actuated to cause downward movement of the insulating operating rod 9. The downward movement of the insulating operating rod 9 causes downward movement of both the movable contact 11 and downward movement of the piston member 41 within the piston chamber 42. The movement of the piston member 41 within the piston chamber 42 forces oil to flow in the direction indicated by the arrows in Figs. 2 and 4. Also pressure formed by the arc 25 within the arcing region 33 will act through the passage 32 provided in the movable contact 11 to communicate with the chamber 30 and hence act against the wall 29 to speed up the downward movement of the movable contact 11 during high current interruption.

In other words, we provide a differential piston action caused by the arcing pressure acting through the passage 32. The arcing pressure acts through the inlet passages 24 and upwardly against the offstanding wall 29. However, the arcing pressure also acts through the passage 32 and on top of the wall 29 and also on top of the contact 11. The differential pressure which causes a net downward force to assist the opening operation of the movable contact 11 is the arcing pressure acting across an area equal to the cross-sectional area of the lower portion of the movable contact 11. During high current interruption this additional driving force speeds up the opening movement.

The downward movement of the piston member 41 within the piston chamber 42 causes oil to flow through the four apertures 47 provided in the cylindrical slide valve 26 and through the inlet passages 24 toward a point P, which in this instance moves at a speed equal to the speed of the movable contact 11. The oil which enters the arcing region 33 at the level P must then traverse the entire arcing region 33 before it is permitted to vent through the aperture 16 provided in the stationary contact 15 as indicated by the arrows in Fig. 2.

It will, therefore, be apparent that we have provided an interrupter in which there are disposed a plurality of passages 24 which terminate at their inner end adjacent the arc 25 and we provide movable valve means 26 movable in response to motion of the movable contact 11 for controlling the flow of fluid through the passages 24. As the movable contact 11 moves downward

5.

during the opening operation, the arc 25 is lengthened and the apertures 47 provided in the cylindrical slide valve 26 successively open the passages 24 to permit the flow of oil therethrough.

It will be noted that the arrangement operates to permit oil to flow through the particular passages 24 which at a particular time terminate adjacent the tip 37 of the movable contact 11. The flow of oil is substantially transversely of the arc 25 and is directed therein at a level with the moving point P in the arcing region 33, which point P moves at a speed which in this instance is directly equal to the speed of movement of the movable contact 11. By making the speed of movement of the movable contact 11 different from the speed of movement of the movable cylindrical slide valve 26 by suitable means such as intermeshing gears, the speed of the point P could be different from the speed of the movable contact 11. For purposes of simplicity we felt it desirable to mechanically connect the slide valve 26 and the movable contact 11 so that the speed of movement of the point P would be the same as the speed of movement of the movable contact 11.

During the closing operation of the interrupter shown in Fig. 2, oil will be drawn upwardly through valve 35 and into chamber 42, the latter then being expanded in volume. During the subsequent opening stroke on no-load operation the volume of the chamber 42 diminishes and the fresh oil now disposed therein will move upwardly through the inlet passages 24 to flush carbonized products of decomposition disposed within the arcing region 33 upwardly and out through the aperture 16 provided in the stationary contact 15. Thus during no-load operation of the interrupter there is a complete flushing of the arcing region 33 because of this unidirectional flow of fresh oil through chamber 42.

In the embodiment of our invention shown in Figs. 5 and 6 we provide a resiliently-mounted relatively stationary contact 52 which cooperates with the movable contact 11 to establish and lengthen an arc 25. A ring-shaped plate 53, threaded to the upper end of the cylindrical slide valve 26, forms a piston member which operates in a piston chamber 42. In this embodiment of our invention the passages formed between the segmental insulating plates 23 form discharge passages 54, which permit the discharge of oil from the arcing region 33. An offstanding portion 55 is integrally formed with contact 11 having apertures 56 formed therein and is threadedly secured to the lower end of cylindrical slide valve 26. Apertures 57 are also formed in the top insulating plate member 58 of the grid structure 19. The top insulating plate member 58 is threadedly secured at 59 to a guide 60 which guides the movement of the relatively stationary contact 52. Apertures 61 are formed in the stationary contact support 62. The stationary contact support 62 may be secured to the contact feet 5 (see Fig. 1) by bolts 13 which may be threadedly inserted into the contact support 62.

It will be apparent that the arc 25 has a fixed arc terminal at the stationary contact 52 and a movable arc terminal at the tip 37 of the movable contact 11. During the opening operation the movable contact 11 moves downwardly together with the cylindrical slide valve 26 and piston member 53. The downward movement of piston member 53 within piston chamber 42 causes a flow of oil out of piston chamber 42

6.

through apertures 57 in the plate member 58 and radially inwardly toward the fixed arc terminal of the arc 25. This oil must then traverse the arcing region 33 before it is permitted to discharge outwardly through the discharge passages 54 and through the apertures 47 provided in the cylindrical slide valve 26. This discharge takes place at a level P, which level in this instance moves at the same speed as the movement of the movable arc terminal. The direction of flow is indicated by the arrows in Figs. 5 and 6.

It will be observed that in Figs. 2, 5 and 10 that the vertical length of the apertures 47 is substantially equal to twice the width of the plates 20, 23. Consequently, at no time is the entrance or discharge of oil from the arcing region 33 entirely prohibited, there always being at least one full width of discharge or entrance passage 54, 24 through which the oil may pass.

It will be apparent from the above description that in the embodiment of our invention shown in Figs. 5 and 6, we have provided valve means responsive to motion of the movable contact 11 for directing a flow of oil adjacent the fixed arc terminal, through the arcing region 33 and discharging out of the arcing region 33 adjacent the movable arc terminal at a level P which moves in this instance at a speed directly equal to the speed of the movable contact 11. As mentioned in connection with Fig. 2 intermeshing gears or other means could be provided to have the speed of movement of the point P in Fig. 5 different from the speed of movement of the movable arc terminal.

Again the valve 35 causes a unidirectional flow of oil through the piston chamber 42 during a complete operation of the interrupter.

In the embodiment of our invention shown in Figs. 7 through 9, we provide a circuit interrupter of modified construction having a piston chamber generally designated by the reference numeral 71. The piston chamber 71 has an enlarged portion 72 and a smaller closed portion 73. An insulating cup-shaped member 74 is threadedly secured at 75 to the offstanding support portion 55 of the movable contact 11. The offstanding support portion 55 again has apertures 56 formed therein. The upper end of the enlarged portion 72 is threadedly secured to an apertured support plate 76 which may be secured to the contact feet 5 of Fig. 1 by any suitable means such as the bolts 13 shown in Fig. 1. Again the valve 35 causes unidirectional flow of oil through the piston chamber 71 during each complete operation of the interrupter.

In Fig. 7 the grid structure 19 is movable with the movable contact 11 being secured to the cup-shaped member 74 by the insulating tie rods 17. During the opening operation the movable contact 11, cup-shaped member 74 and grid structure 19 move downwardly as a unit from the enlarged portion 72 into the smaller closed portion 73 of the piston chamber 71. This causes an upward flow of oil radially inwardly toward the movable arc terminal, upwardly within the arcing region 33 and outwardly through the discharge passages 54 at a level P which, in this instance, is adjacent the stationary arc terminal. It will be apparent that the grid structure 19 coacts with the shoulder 77 to permit the discharge of oil through the discharge passages 54 only at a level adjacent the fixed arc terminal. It will be noted that the discharge passages 54 are uncovered successively as they are brought below the stationary

contact tip, while the outer openings of these discharge passages 54 are successively sealed off as they move below the shoulder 71 integrally formed with the piston chamber 71.

It is also to be observed that the pressure in the exhaust chamber, generally designated by the reference numeral 78, in Fig. 7, tends to accelerate the moving contact 11 by acting downwardly on the moving grid 19. The size of the apertures 76a determines the magnitude of the pressure in the exhaust chamber.

In the embodiment of our invention shown in Figs. 10-12, we disclose an arrangement similar to that shown in Fig. 5. However, we provide a passage 32 through the movable contact 11 to permit differential piston action to accelerate the opening movement of the movable contact 11 during high current interruption. In other words, the arcing pressure acts upwardly on the ring-shaped piston 53, but also acts downwardly on the support portion 55 by acting through the passage 32. The differential piston area is, therefore, the area of the support portion 55 minus the area of the ring-shaped piston member 53, and the arcing pressure acting on this differential piston area tends to accelerate the movement of the moving contact 11 during high current interruption.

As in Fig. 2, we have a chamber 30 which is expandable during the opening operation and contractable during closing operation. The slide valve action of cylindrical slide valve 26 is the same as in Fig. 5. Therefore, a further description concerning this feature is not necessary for a full understanding of this embodiment of our invention. It will be noted that in Fig. 10 the discharge of oil takes place through the discharge passages 54 at a level P, which level moves at the same speed as the movable contact 11. As previously mentioned, a different speed ratio could be obtained by means permitting relative movement of the contact 11 with cylindrical slide valve 26, such as intermeshing gears or other suitable means well known in the art.

Although we have illustrated our invention as adapted to particularly desirable forms of circuit interrupters which use a suitable arc extinguishing liquid such as oil, it is to be clearly understood that some aspects of our invention are not limited to these particular types of interrupters but are adapted to the use of any fluid which need not be oil but could be a gas or even air. Also separate sources of pressure to drive such fluids as gases or liquids could be used instead of relying on piston action of the moving parts.

Although we have shown and described specific structures, it is to be clearly understood that the same were merely for purposes of illustration and that changes and modifications may be readily made by those skilled in the art without departing from the spirit and scope of the appended claims.

We claim as our invention:

1. In a circuit interrupter, means for establishing an arc, means defining a plurality of stationary passages terminating at one end closely adjacent to the arc, and a cylindrical slide valve substantially surrounding the arc for controlling the flow of fluid through the plurality of passages.

2. In a circuit interrupter, movable means for establishing and lengthening an arc, means defining a plurality of stationary passages terminating at one end closely adjacent to the arc, and a cylindrical slide valve substantially surrounding the arc responsive to motion of the first-

mentioned means for controlling the flow of fluid through the plurality of passages.

3. In a circuit interrupter, an annular stationary contact, a movable contact cooperable with the stationary contact to establish an arc, stationary means partly of insulating material for forming a plurality of inlet passages terminating adjacent the path of movement of the movable contact, a piston chamber containing fluid, a piston member secured to and movable with the movable contact within the piston chamber, the piston member having an aperture formed therein to successively open the inlet passages while meanwhile closing others and thus permit fluid forced under pressure from opening movement of the piston member to successively pass through the inlet passages to the arc, and at least part of the fluid discharging through the annular stationary contact.

4. In a circuit interrupter, a stationary contact, a movable contact cooperable with the stationary contact to establish an arc, stationary means partly of insulating material forming a plurality of discharge passages leading away from the path of movement of the movable contact, a piston member secured to and movable with the movable contact, the piston member having an aperture formed therein to successively open the discharge passages during the opening operation while meanwhile closing others, the piston member forcing the fluid adjacent the stationary contact toward the arc and at least part of the fluid discharging away from the arc through the discharge passages upon the opening thereof.

5. In a circuit interrupter, a stationary contact, a movable tubular contact cooperable with the stationary contact to establish an arc, stationary means partly of insulating material forming a plurality of discharge passages leading away from the path of movement of the movable tubular contact, a differential piston member secured to and movable with the movable contact, the differential piston member having an aperture formed therein to successively open the discharge passages during the opening operation while meanwhile closing others, the differential piston member being driven by arcing pressure acting through the movable tubular contact to force fluid adjacent the stationary contact toward the arc, and at least part of the fluid discharging away from the arc through the discharge passages upon the opening thereof.

6. In a circuit interrupter, a piston chamber having an enlarged portion and a smaller closed portion, a stationary contact and a movable contact both disposed within the piston chamber and cooperable to establish an arc, a grid structure partly of insulating material and secured to and movable with the movable contact from the enlarged portion of the piston chamber to the smaller closed portion thereof, the grid structure operating as a piston within the piston chamber to force fluid adjacent the movable contact and into the arc, the grid structure forming a plurality of discharge passages for the discharge of fluid from said arc, the discharge passages being successively closed upon opening movement of the grid structure into the smaller portion of the piston chamber.

7. In a circuit interrupter, means at least partly of insulating material forming an arc passage, means for establishing an arc within the arc passage, the first-mentioned means also providing a plurality of fluid passages disposed axially along the arc passage whereby fluid may flow

through the fluid passages, and means for successively opening the fluid passages one by one while at the same time successively closing others of said fluid passages so that fluid may pass only through the fluid passages which are opened by said last-mentioned means.

8. In a circuit interrupter, stationary means at least partially of insulating material forming an arc passage, means for establishing an arc within the arc passage, the first-mentioned means also providing a plurality of fluid passages spaced axially along the arc passage whereby fluid may flow through the fluid passages, and valve means including a movable apertured member for successively opening the fluid passages one by one while at the same time successively closing others of said fluid passages so that fluid may pass only through the fluid passages which are opened by said valve means.

9. In a circuit interrupter, stationary means at least partially of insulating material forming an arc passage, means venting the arc passage only adjacent one end thereof, means for establishing an arc within the arc passage, the first-mentioned means also providing a plurality of fluid passages disposed axially along the arc passage whereby fluid may flow through the fluid passages into the arc passage, and valve means including a movable apertured member for successively opening the fluid passages one by one while at the same time successively closing others of said fluid passages so that fluid may enter the arc passage only through the fluid passages which are opened by said valve means.

10. In a circuit interrupter, stationary means at least partially of insulating material forming an arc passage, means for forcing fluid into the arc passage adjacent one end thereof, means for establishing an arc within the arc passage, the first-mentioned means also providing a plurality of spaced fluid passages extending axially along the arc passage whereby fluid may exhaust out of the arc passage through the fluid passages, and valve means including a movable apertured member for successively opening the fluid passages one by one while at the same time successively closing others of said fluid passages so that fluid may exhaust out of the arc passage only through the fluid passages which are opened by said valve means.

11. In a circuit interrupter, means at least partially of insulating material forming an arc passage, means for establishing an arc within the arc passage, the first-mentioned means also providing a plurality of pairs of fluid passages spaced axially along the arc passage whereby fluid may pass through each pair to strike at least opposite sides of the arc within the arc passage, and means for successively opening the pairs of fluid passages one by one while at the same time successively closing others of said pairs of fluid passages so that fluid may pass only through the pairs of fluid passages which are opened by said last-mentioned means.

12. In a circuit interrupter, relatively stationary means at least partially of insulating material forming an arc passage, means for establishing an arc within the arc passage, the first-mentioned means also providing a plurality of pairs of fluid passages spaced axially along the arc pas-

sage whereby fluid may pass through each pair to strike at least opposite sides of the arc within the arc passage, and valve means including a movable apertured member for successively opening the pairs of fluid passages one by one while at the same time successively closing others of said pairs of fluid passages so that fluid may pass only through the pairs of fluid passages which are opened by said last-mentioned means.

10 13. In a circuit interrupter, stationary means at least partially of insulating material forming an arc passage, means venting the arc passage only adjacent one end thereof, means for establishing an arc within the arc passage, the first-mentioned means also providing a plurality of fluid inlet passages disposed axially along the arc passage whereby fluid may flow through the fluid passages into the arc passage, and means for successively opening the fluid passages one by one

15 while at the same time successively closing others of said fluid inlet passages so that fluid may pass only through the fluid inlet passages which are opened by said last-mentioned means and exhaust out said venting means.

20 14. In a circuit interrupter, means at least partially of insulating material forming an arc passage, means forcing fluid into the arc passage adjacent one end thereof, means for establishing an arc within the arc passage, the first-mentioned

25 means also providing a plurality of fluid exhaust passages disposed axially along the arc passage whereby fluid may exhaust away from the arc passage out through the fluid exhaust passages, and valve means for successively opening the fluid

30 35 exhaust passages one by one while at the same time successively closing others of said fluid exhaust passages so that fluid may exhaust out of the arc passage only through the fluid exhaust passages which are opened by said last-mentioned

40 means.

15 16. In a circuit interrupter, relatively stationary means at least partially of insulating material forming an arc passage, means for establishing an arc within the arc passage, the first-mentioned means also providing a plurality of pairs of fluid exhaust passages spaced axially along the arc passage whereby fluid may exhaust out of the arc passage through the fluid exhaust passages, and valve means for successively opening

45 50 the pairs of fluid passages one by one while at the same time successively closing others of said pairs of fluid passages so that fluid may exhaust out of the arc passage only through the pairs of fluid exhaust passages which are opened by said last-mentioned means.
